UNITED STATES PATENT OFFICE.

HOMER E. ROBERTSON, OF WINNETKA, ILLINOIS, ASSIGNOR TO GOETZ BRASS COMPANY, A CORPORATION OF ILLINOIS.

WASTE FIXTURE.

Application filed January 12, 1928. Serial No. 246,110.

This invention relates to waste fixtures and aims to provide an improved fixture of this character which is attractive though inconspicuous and which may be removed for 5 repair or otherwise from the exposed side of the device to which it is applied.

The nature of the invention may be readily understood by reference to one illustrative embodiment thereof shown in the accompanying drawing.

In said drawing:

Fig. 1 is a vertical section through one end of a built-in bath tub or the like showing a waste fixture applied thereto.

Fig. 2 is a vertical section of an installed waste fixture, the valve element thereof being shown in open position.

Fig. 3 is a plan section taken on line 3—3 of Fig. 2.

Fig. 4 is a plan view illustrating the angular movement necessary to operate the valve.

The illustrative waste fixture is herein shown applied to a built-in bath tub 10, that is, a tub some of whose sides abut a wall.

In installations of this character, appearance is of prime importance and it is, therefore, desirable to conceal as much of the accessory plumbing structure as possible. In the arrangement here shown the waste end of the tub abuts the wall 11, the tub being so designed as to provide a space 12 at its end and below its bottom for an overflow pipe 13 and waste pipe 14. The overflow pipe 13 is connected with the overflow opening 15 of the tub in an appropriate manner and this opening is advantageously covered by a strainer 16 which is designed to give the connection a neat finish.

The waste pipe 14 is connected with the waste opening 17 in the tub bottom by a flanged coupling or nipple 18 which screws into the threaded elbow 19 of the waste pipe. The margin 20 of the waste opening is clamped between the flanges 21 and 22 of the elbow and coupling, respectively. A gasket 23 of rubber or the like is advantageously interposed between the flange 21 and the tub bottom to insure a tight joint. The upper surface 24 of flange 22, here shown as flat, lies flush with or a little below the tub bottom. A valve in the form of a plate 25 seats against the upper surface of flange 22 and for this purpose is in this case provided with a flat or substantially flat lower face 26.

While the lower face of the valve may appear 55 flat, it may be machined so that only a portion of its surface makes a seating contact with flange 22,—so as to concentrate the weight of the valve on a smaller seating area. The upper face 25 of the valve is flat or 60 slightly convex and is beveled or rounded at its upper edge so that when seated it presents a smooth surface without any corners, being in effect practically a continuation of the surface of the tub bottom. Such a construction 65 is ideal for bath tubs not only from the standpoint of appearance but because it eliminates the waste strainer or the depressed or projecting waste closure, which are uncomfortable and frequently unsightly and difficult 70 to keep clean. The exposed face of the valve advantageously has a polished nickel plated finish or such other finish as harmonizes with the tub and other fittings.

The valve is held in position relative to 75 its seat by a guide in the form of vanes 27 (three in this case) which allow vertical and rotative movement of the valve but by engagement with the inner face of the nipple 18 prevent its lateral displacement. The vanes 80 serve to divide the waste passage into a plurality of passages of sector-shaped cross-section which effectively prevent the formation of a vortex- or vortices in the escaping water which would seriously limit the capacity of the waste passage to carry away 85 waste water.

Opening of the valve by a vertical movement thereof above its seat (thereby providing an annular waste opening 28 for the escape of water) is effected in this instance by rotation which involves a vertical camming action. The cam means are here shown as inclined cam surfaces 29 advantageously formed integral with the coupling 18 and 90 engaging respectively the lower edges of the guide vanes 27. Thus rotative movement of the valve causes the guides to move up or down (as the case may be) the inclined cam faces. Spaces 30 are provided beyond the lower ends of the cam surfaces which receive the vanes after they travel beyond the ends of the cams, thereby allowing the valve 95 to seat freely and bringing the entire weight of the valve upon the valve seat. The upper ends 31 of the cam surfaces are flattened so that the valve will remain in open position 100 after it has been once moved into that position.

tion. Stops 32 at the upper ends of the cam faces limit the rotative movement of the valve.

A small laterally extending or eccentric projection 33 (which is well rounded to eliminate any uncomfortable surfaces) is advantageously provided on the upper side of the valve so that the valve may be rotated to open or close the same by a slight lateral pressure applied by the foot, thereby avoiding the necessity of stooping to operate the valve or of putting the hands in the water. For this purpose the valve should be inserted in the coupling 18 so that the projection 33 extends laterally when the valve is closed. To open the valve it is simply necessary to push or kick the projection through a small distance in the direction indicated by the arrow in Fig. 4.

While the valve may be removed from the coupling 18 simply by lifting it, a flexible connection in the form of a bead chain 34 prevents the complete detachment of the valve so that children particularly, cannot completely remove the valve and possibly lose it. In the present case one end of the chain is connected by a screw 35 to the lower edge of the coupling 18 and the other end by a similar screw 36 to the lower edge of the guide vanes in the valve. If it be necessary to detach the valve this may be done by unscrewing the screw 36.

Necessary repairs and replacements of parts may be made from the exposed side of the tub. For example, if it be necessary to renew either the valve or coupling (the only elements ever likely to require replacement), all of this may be done from the exposed side of the tub and without access to the concealed or enclosed side. Thus it is unnecessary to provide an unsightly and expensive panel on the opposite face of the wall for the purpose of giving access to the back or concealed face of the tub. Furthermore, no waste control elements obstruct the overflow pipe, leaving the latter free to function efficiently to carry away overflow water.

Obviously the invention is not limited to the details of the illustrative construction, since these may be variously modified. Moreover it is not indispensable that all features of the invention be used conjointly since various features may be employed in other combinations and sub-combinations.

Having described one embodiment of my invention, I claim:

1. An internally removable waste fixture for bath tubs or the like comprising in combination with the waste opening in the tub bottom, a waste pipe having an opening registering with said waste opening, a coupling connected with said pipe opening and extending into the waste opening and having a flange engaging the upper margin of the tub opening and forming a tight joint there-

with, a valve having a substantially flat upper face and having a lower face adapted to seat against said coupling flange, said upper face forming substantially an unbroken surface with the tub bottom, valve guiding means extending into the coupling and engaging cam means in said coupling and cooperating therewith to raise and lower said valve upon rotation thereof, and a small eccentric projection on the upper face of said valve extending laterally only a sufficient distance to enable said valve to be opened and closed by a kick delivered against said projection, said projection merging into the upper surface of the valve surface so as not to provide any sharp or interfering projection. 70 75 80

2. An internally removable waste fixture for bath tubs or the like comprising in combination with the waste opening in the tub bottom, a waste pipe having an opening registering with said waste opening, a coupling connected with said pipe opening and extending into the waste opening and having a flange engaging the upper margin of the tub opening and forming a tight joint therewith, a valve having a substantially flat upper face and having a lower face adapted to seat against said coupling flange, said upper face forming substantially an unbroken surface with the tub bottom, valve guiding means extending into the coupling, said coupling being provided with relatively steep cam surfaces engaging said guiding means whereby said valve may be fully opened and closed by rotation thereof through only a small portion of a single revolution, and provided with means which serve to hold said valve against self-closing when rotated to its fully open position, said cam surfaces being designed to enable said valve to close by gravity after an initial closing movement thereof, and a small eccentric projection on the upper face of said valve extending laterally only a sufficient distance to enable said valve to be opened and closed by a kick delivered against said projection, said projection merging into the upper surface of the valve surface so as not to provide any sharp or interfering projection. 90 95 100 105 110

3. An internally removable waste fixture for bath tubs or the like comprising in combination with the waste opening in the tub bottom, a waste pipe having an opening registering with said waste opening, a coupling connected with said pipe opening and extending into the waste opening and having a flange engaging the upper margin of the tub opening and forming a tight joint therewith, a valve having a substantially flat upper face and having a lower face adapted to seat against said coupling flange, said upper face forming substantially an unbroken surface with the tub bottom, cam means associated with said coupling, said valve provided with guiding means extending into said 115 120 125 130

- coupling and engaging said cam means so as to be free to be lifted vertically clear of said coupling, said cam means being designed so that said valve may be fully opened or closed by rotation thereof through only a small portion of a single revolution, and provided with means which serve to hold said valve against self-closing when rotated to its fully open position, said cam means being designed to enable said valve to close by gravity after an initial closing movement thereof, and a small eccentric projection on the upper face of said valve extending laterally only a sufficient distance to enable said valve to be opened and closed by a kick delivered against said projection, said projection merging into the upper surface of the valve surface so as not to provide any sharp or interfering projection.
4. An internally removable waste fixture for bath tubs or the like comprising in combination with the waste opening in the tub bottom, a waste pipe having an opening registering with said waste opening, a coupling connected with said pipe opening and extending into the waste opening and having a flange engaging the upper margin of the tub opening and forming a tight joint therewith, a valve having a substantially flat upper face and having a lower face adapted to seat against said coupling flange, said upper face forming substantially an unbroken surface with the tub bottom, valve guiding means extending into the coupling, cam means in said coupling on which said guiding means rest so that said valve may be freely lifted clear of said coupling, said cam means cooperating with said guiding means to raise and lower said valve upon rotation thereof, a small eccentric projection on the upper face of said valve extending laterally only a sufficient distance to enable said valve to be opened and closed by a kick delivered against said projection, and a flexible element connecting said valve with said coupling and cooperating to permit said valve to be lifted clear of the latter but preventing complete separation of the valve from the coupling.

In testimony whereof, I have signed my name to this specification.

HOMER E. ROBERTSON.
